PAPER PICKER

Malcolm Gilbert Donaldson, Okeechobee, Fla.

Application July 24, 1944, Serial No. 546,283

3 Claims. (Cl. 294—61)

The present invention relates to pickers for use in picking up papers, rags, and other trash from school grounds, parks, lawns, picnic grounds and other places.

The general object is to provide a picker of the character stated, with new and important improvements over devices thus far patented for similar purposes, in which a spike may be used for a pick, and when said spike is broken it may be replaced by another with as little inconvenience as possible.

Another object is to provide a picker of the character stated which is sufficiently strong, yet light, handy, neat and attractive, simple in construction, with no parts to get out of order other than, perhaps, the spike; and even this to last indefinitely with reasonable care; a picker that is comparatively inexpensive to manufacture, easy to repair, and economical in operation and upkeep.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a side elevation of the picker constructed according to the invention with a portion of the handle broken away.

Figure 2 is a similar view taken on an enlarged scale with parts broken away and parts shown in section.

Figure 3 is a side elevation of the spike taken on an enlarged scale.

Figure 3a is a plan view of such spike.

Figure 4 is a longitudinal section of the socket member or spike-holder taken on an enlarged scale.

Figure 4a is a top plan view of such socket member.

Referring more particularly to the drawing my invention includes a spike holder as shown in Figure 4, a handle 5, preferably made of wood, as shown in Figures 1 and 2, its lower end fitting snugly into the upstanding compartment or arms 13 of the spike holder, and being further secured, if desired, by small screws 6 each passing through one of a number of small openings in the flange 14 of the spike holder; and a spike, Figure 3, an upper portion of which fits snugly in the opening 9 of the base 8 of the spike holder and is held firmly in place by the set screw 7.

The spike holder comprises the base 8 and an upstanding socket or compartment 13, preferably

cylindrical for receiving the lower end of handle 5. (Three or more arms could serve this purpose in lieu of the compartment or socket 13, if desired.)

5 The compartment or socket 13 as disclosed in the drawing, Figures 2 and 4, has a flange 14 at the top, through which three small holes 6 appear. The purpose of this flange is to make it easier to fix the spike holder onto the end of the handle by affording something to strike against, if desired while driving the spike holder onto the handle. This could be done by placing the pointed end of a punch or screw driver against the flange, and striking the other end of said punch or screw driver lightly with a hammer. The purpose of the holes 6 is to receive small screws which may be used if desired to still further secure the spike holder onto the end of the handle. To determine when the end of the handle has 10 reached the bottom of the compartment 13, the depth of said compartment could be measured and this measure marked on the handle after measuring upward on said handle from its lower end; or two other holes 16 could be made opposite each other at the lower limit of the compartment through which it could be seen when the lower end of the handle reached said limit.

15 The base 8 of the spike holder is provided with a central opening 9 for receiving and releasing an upper portion of the spike, Figure 3, and in which said spike fits snugly, said central opening permitting unobstructed contact of spike with end of handle in compartment 13. Base 8 provides also a lateral opening perpendicular to the central opening 9, located at a convenient point between the two ends of the central opening 9, and threaded for receiving and releasing the set screw 7 which may be provided with any form of head desired. A comparatively large circular milled head as shown in the drawing, however, or some other form that could be easily operated with thumb and finger would probably be preferred as the spike could then be placed or replaced without the aid of any other tool. This lateral opening is provided with a projection 10 extending outward from the base 8 sufficient to provide ample support to the set screw 7. This projection 10 may extend outward to an extent greater or less than is indicated in Figure 4, if desired.

20 The spike 15, Figure 3, may, if desired, be provided with a catch or notch 11, into which the end of the set screw 7 may be received. The purpose of this would be to hold the spike more securely, if necessary, in the opening 9 of the base

8. The spike, Figure 3, may also be provided at the top with a sharp point or prong 12 which may be easily worked into the end of the wooden handle 5. This point 12 would help to prevent any lateral sway of the spike inside of the base in case the spike does not fit snugly enough inside the opening 9 of the base 8. Otherwise, the point 12 would not appear to be necessary.

The wooden handle 5 is rounded at the top to prevent injury to the hand of the user. It is otherwise cylindrical and of any length to suit the user, say, usually about 20 to 28 inches long.

The operation of my invention is as follows:

The handle of the paper picker being held by the hand of the user, with spike directed downwardly at a piece of paper on the ground, a thrust is made downwardly until the spike has pierced the paper, causing same to adhere to the spike. The user then proceeds to the next piece of paper or other trash that is to be picked up, and repeats the same activity as before. He continues this way until he has an accumulation of papers on the spike sufficient to need removing from same. The paper picker is then lifted to such position and in such manner as will enable the user to draw the spike across the edge of the top of a waste-basket, garbage can, or other receptacle which may be carried by the user or by one or two assistants. Papers are thus deposited into the receptacle without the necessity of being touched by hand.

If the point of the spike becomes dull, it may be sharpened, and if it becomes broken, sufficiently to need replacement, it can be readily removed from the holder by loosening the set screw 7 and pulling it out. Another similar spike is then easily inserted in its place. Give the spike a few turns back and forth with the hand until the point 12 penetrates its length into the wooden handle, leaving it with the notch 11 facing the end of the set screw 7, which is then tightened until it presses the spike firmly, holding it securely in opening 9 of base 8 of the holder.

The metal parts while neat and attractive can, nevertheless, be manufactured cheaply enough. They can be made of material having a nickel, silver, or golden appearance, or made of cheaper, though strong and substantial material and painted and varnished over. The spike is preferably made of hardened steel such as is used in ice picks and that will not bend.

And now, a word about the handle. In janitors' supply and storage rooms in public school buildings, around homes, and in other places, are often found old worn-out brooms. The handles of these old brooms, as good as ever, may be sawed off in such lengths as to suit the user of the paper picker, and used as handles for the same. Such pieces of old broom handles can then be repainted if desired, and varnished, keeping the paper-picker attractive.

While size has no place in an application for a patent, it is recommended that this socket member or spike-holder be made in two sizes, one to fit a wooden handle, cylindrical in shape, and having a $\frac{3}{4}$ inch diameter, and another size to fit such wooden handle having a 1-inch diameter; since broom handles are usually made in these sizes. The handles of old worn-out brooms, sawed in lengths to suit the user, could then be used as handles for the paper-picker, since the broom handles are usually as good as ever, when the broom is worn out. Such handles, if desired, could be repainted in attractive colors and varnished, making them attractive to school children, who, it is thought, would delight to handle and use them in cleaning up papers, etc. from school grounds.

It is recommended that the spike be made in sizes such as that of ice-picks; $5\frac{1}{2}$ to $6\frac{3}{4}$ inches long, diameter accordingly, strong, sharp, and sufficiently tapering to penetrate the ground easily.

I do not limit my invention to the exact details and construction herein disclosed, as changes may be made therein without departing from the spirit of the invention.

What is claimed is:

1. A paper picker or the like comprising a spike holder having aligned communicating handle and spike sockets opening respectively at opposite ends of the holder, a handle having an end received in the handle socket, and a spike having a tang end fitting in the spike socket, and a connecting prong between the spike and handle.

2. A paper picker or the like comprising a spike holder having aligned communicating handle and spike sockets opening respectively at opposite ends of the holder, a wooden handle having an end received in the handle socket, a metal spike having a tang end fitting in the spike socket, and a connecting prong on the inner end of the spike embedded in the wood of the inner end of the handle.

3. A paper picker or the like comprising a spike holder having aligned communicating handle and spike sockets opening respectively at opposite ends of the holder, a wooden handle having an end received in the handle socket, a metal spike having a tang end fitting in the spike socket, the inner ends of the handle and spike abutting through the communicating sockets, and a cone prong projecting from the inner end of the spike and embedded in the wood of the inner end of the handle, the base of the cone prong being narrower than the inner end of the spike to provide a shoulder about the prong base for abutting against the inner end of the handle.

60 MALCOLM GILBERT DONALDSON.
